SNUBBER

David M. Light, Chicago, Ill., assignor to American Steel Foundries, Chicago, Ill., a corporation of New Jersey

Application July 27, 1942, Serial No. 452,423

22 Claims. (Cl. 267—9)

My invention relates to a snubber or a friction absorbing device of a form designed particularly to replace a coil spring as commonly used in railway equipment.

The general object of my invention is to devise a novel form of snubber wherein the compression spring may have associated therewith top and bottom followers each presenting a semi-cylindrical barrel or stem portion within said compression spring for frictional engagement therewith and so arranged as to accommodate a friction shoe urged in engagement with each of said portions by resilient means associated therewith.

A specific object of my invention is to arrange such a structure as that described in such manner as to afford a relatively steep angle of frictional engagement between said shoe and one of said stem portions and a relatively flat angle of engagement with the other of said stem portions.

A more specific object of my invention is to devise a snubber such as that described wherein an automatic interlocking means may be provided by affording abutting means on the shoe and one of the follower stems in such manner as to limit the expansion of the device.

My invention also comprehends such an arrangement as that described wherein one of the followers and the friction shoe may be afforded pin openings which may be brought into alignment in assembling the device in such manner as to facilitate said assembly after which said pin may be removed, permitting the device to expand to normal height.

Yet another object of my invention is to devise a snubber having top and bottom followers seated against opposite ends of a compression spring and in frictional engagement therewith, one of said followers affording a spring seat on which resilient means may be mounted for abutment with a friction shoe engaging both of said follower stems.

In the drawings, Figure 1 is a vertical sectional view taken on one diameter of my novel form of friction device and approximately in the plane indicated by the line 1—1 of Figure 2. Figure 2 is a top plan view of the structure shown in Figure 1, half in section, the section being taken approximately in the horizontal plane indicated by the line 2—2 of Figure 1.

Figure 3 is a view comparable to Figure 1 showing a modification of my novel snubber, the view being taken in a vertical plane along one diameter of the device and approximately in the plane indicated by the line 3—3 of Figure 4. Figure 4 is a top plan view, half in section, of the structure

shown in Figure 3, the section being taken approximately in the horizontal plane indicated by the line 4—4 of Figure 3.

Describing the structure in detail and referring first to the arrangement shown in Figures 1 and 2, my novel snubber comprises a top follower 2 having a base 4 chamfered as at 6 to afford a rocking seat at 8 for one end of the device, said base 4 having a central opening 9 affording positioning means for the device. The base 4 may also have an annular flange affording a seat as at 10 for the compression spring 12, the end turn of said spring 12 being afforded a satisfactory fit with said follower by coring away as at 11 the stem portion 16 adjacent the base 4. The spring 12 may be of any convenient section, shown here as octagonal, so as to afford on the successive turns thereof friction surfaces for engagement as at 15, 15 with the semi-cylindrical stem portion 16 of the follower 2, said stem portion having the base web 18 affording a seat as at 20 for the auxiliary spring 22 which may be supported in position on said seat by the retaining lug 24. The upper end of the auxiliary spring 22 may seat as at 26 against the shelf portion 28 of the friction shoe 30, said shelf portion 28 presenting on its upper face a diagonally arranged friction surface having engagement as at 32 with a complementary friction surface afforded on the diagonal web 34 integrally formed with the stem 16 of the follower 2.

The friction shoe 30 may present on one face thereof a V-shaped friction surface having engagement as at 36 with the complementary V-shaped surface 38 formed on the semi-cylindrical stem portion 40 of the bottom follower 42, said bottom follower having a base portion 44 chamfered as at 46 to form a rocking seat as at 48 for the other end of said device, said base 44 also having the central opening cored out as at 49. The base 44 may also have an annular flange affording a seat as at 50 for the bottom end of the compression spring 12. The stem portion 40 of the bottom follower like that of the upper follower may have frictional engagement as at 52, 52 with the aligned internal friction faces on the respective turns of said compression spring 12.

The upper end of the friction shoe 30 may have a vertical slot 54 defined at its lower extremity by the shoulder 56 affording abutment as at 58 for the lug 60 formed at the upper end of the stem 40, the engagement of said lug with the shoulder 56 limiting the expansion of said device

and affording an automatic lock therefor after the parts are assembled.

It should be noted that the V-shaped engaging surfaces on the shoe 30 and the stem 40 are relieved adjacent the apex of the V as clearly indicated at 62 in order to accommodate working in of the friction surfaces therealong and affording satisfactory fit therebetween.

The upper face of the friction shoe 28 is afforded a vertical pin opening 64 which in assembling may by clamping means be brought into alignment with the pin openings 66 in the web 34 of the top follower, after which a retaining pin may be positioned therein to hold the top follower, the friction shoe 28 and the auxiliary spring in assembled relationship. Thereafter, these parts may be forced into the upper end of the compression spring 12 with which the bottom follower may previously have been associated, the compression applied being sufficient to urge the shoe downwardly until the shoulder 56 is engaged with the lug 60 as previously described.

The modification illustrated in Figures 3 and 4 differs from that shown in Figures 1 and 2 in that the frictional engagement between the shoe and the top follower is at the base of said follower instead of adjacent the upper end thereof. In this arrangement the top follower, generally designated 102, may have the base 104 cored out centrally thereof as at 106 to afford positioning means therefor, said base being chamfered as at 108 to permit rocking of the device upon the seat provided on said base at 110. The base 104 may afford an annular seat as at 112 for the main compression spring 114, the respective turns of which may present vertically aligned friction surfaces 116, 116 for engagement as at 118, 118 with the semi-cylindrical stem portion 120 formed as an integral part of the top follower 102, said stem portion adjacent the base 104 being relieved as at 122 to afford satisfactory fit with the adjacent end turn of the compression spring 114. The lower end of the stem portion 120 may be formed with a diagonal web 124 presenting on its upper face a diagonally arranged friction surface for engagement as at 126 with the complementary face formed on the shelf portion 128 of the friction shoe 130. The shelf portion 128 of the friction shoe may have a horizontal top surface affording a seat as at 132 for the auxiliary spring 134, said spring being positioned thereon by the lug 136. The frictionally engaging shoe 130 and the web 124 may have vertically alignable pin openings 138 and 140 respectively, said pin openings serving the purpose described for the previous modification.

The upper end of the auxiliary spring 134 may seat as at 142 against the base 104 of the top follower and be positioned thereon by means of the lug 144.

The upper end of the friction shoe 130 may be formed with a slot 146, the lower extremity of which may be defined by the shoulder 148 which may be engaged as at 150 by the lug 152 to limit the expansion of said device and retain the parts in normal assembled relationship. The lug 152 is formed at the upper extremity of the stem portion 154 of the bottom follower, generally designated 156, the stem portion 154 being of semi-cylindrical form and having frictional engagement as at 158, 158 with the successive turns of the main compression spring 114, the bottom turn of said spring being afforded a satisfactory fit

with the stem portion 154 by coring it away as at 160 adjacent the base 161.

As in the previous modification, the stem portion 154 of the bottom follower is formed with a V-shaped friction surface tapering slightly from the vertical and having frictional engagement as at 162 with a complementary surface formed on the friction shoe 130 with respective V-shaped faces of the shoe and the follower stem being afforded slight clearance adjacent the apex of the V as at 164 in order to accommodate the working in of said surfaces to a good fit.

The base 161 of the bottom follower may afford a seat as at 166 for the main compression spring 114 and the outer face of said base may be chamfered as at 168 to afford a rocking seat as at 170 for the bottom of said device. Said base may also be cored away as at 172 centrally thereof to permit positioning of the device with respect to the supporting member.

It will thus be seen that in both modifications of my novel frictional arrangement, the wedge-like friction shoe has a tapering V-shaped surface in complementary engagement with the bottom follower of the device and has a diagonally arranged flat friction surface engagement with a web portion of the top follower, said friction shoe being urged into wedge engagement with both of said followers by means of an auxiliary spring or resilient means compressed between said shoe and one of said followers. In both arrangements the top and bottom followers are formed with semi-cylindrical stem portions having outer faces engaging aligned friction surfaces on the respective turns of the outer compression spring, the opposite ends of which may seat against respective followers. It will be understood by those skilled in the art that I may vary the angles of engagement between the friction shoe and the respective followers in order to modify the character or degree of friction developed.

It should be noted that in both modifications the excess of the auxiliary spring is arranged somewhat off the vertical as may be clearly seen by comparing the axis A-B of the auxiliary spring 134 (Figure 3) with the vertically arranged axis X-Y of the friction device. The said auxiliary spring axis is thus arranged in order that when the device is placed under compression and the friction shoe 130 moves to the right (Figure 3), the lower end of the axis A-B of the auxiliary spring 134 will also be shifted to the right. This arrangement of the axis of the auxiliary spring is such that as the friction shoe 130 moves laterally with compression or release of the device, the spring will be equally stressed in opposite directions at the extremities respectively of the down-stroke and the upstroke. If the axis of the auxiliary spring were vertically arranged with the device in expanded position as illustrated in Figure 3, the stress resulting in the lateral movement of the shoe would be twice that which results in the arrangement illustrated because the position of the bottom of the spring with respect to the top thereof would be shifted laterally a distance twice as great as that illustrated.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a snubber, a main spring, top and bottom

followers seated against opposite ends of said spring with semi-cylindrical stems extending therewithin for frictional engagement therewith, one of said stems having a diagonal web with a friction face and the other of said stems having a V-shaped friction surface, a wedge shoe engaging said face and said surface, and resilient means compressed between said shoe and one of said followers, said shoe and said diagonal web having vertically arranged alignable retaining pin openings.

2. In a friction device, a compression spring, top and bottom followers seated thereagainst and having semi-cylindrical stems extending therewithin, one of said followers having a diagonal web with a friction face and a horizontal web forming a spring seat, the other of said stems having a friction surface, a wedge shoe engaging said face and said surface, and resilient means compressed between said shoe and said horizontal web, said friction surface being V-shaped and tapering.

3. A friction device having a compression spring, top and bottom followers seated against respective ends thereof with stems extending therewithin in overlapping relationship for frictional engagement therewith, said stems presenting diagonally arranged friction surfaces, a wedge shoe in slidable engagement with said surfaces, and resilient means associated with and compressed between one of said followers and said shoe, one of said surfaces being arranged at a relatively steep angle as compared with the other of said surfaces.

4. A friction device comprising a compression spring, spaced followers seated against opposite ends of said spring with friction stems extending in overlapping relationship therewithin for frictional engagement therewith, diagonally arranged friction faces on said stems, a wedge shoe engaging said faces, and resilient means associated with and compressed between said shoe and one of said stems, the faces on respective stems being arranged at different angles, one of said faces being arranged at a relatively acute angle as compared with the other thereof.

5. A friction device comprising a compression spring, spaced followers seated against opposite ends of said spring with friction stems extending in overlapping relationship therewithin, diagonally arranged friction faces on said stems, a wedge shoe engaging said faces, resilient means compressed between said shoe and one of said stems, the faces on respective stems being arranged at different angles, and abutting means on said shoe and one of said stems affording interlocking means for said device.

6. A friction device having a compression spring, top and bottom followers seated against respective ends thereof with stems extending therewithin in overlapping relationship, said stems presenting diagonally arranged friction surfaces, a wedge shoe in slidable engagement with said surfaces, and a coil spring compressed between said shoe and one of said followers, the axis of said coil spring diverging in opposite directions from the vertical, respectively, as said device is compressed and released.

7. In a snubber, a compression spring, top and bottom followers having semi-cylindrical stems extending within said spring for frictional engagement therewith, one of said stems having a diagonal web with a friction surface and the other of said stems presenting a V-shaped friction face, a wedge shoe engaging said surface and

face, and resilient means compressed between said shoe and one of said stems.

8. In a friction device, a compression spring, top and bottom followers seated thereagainst and having semi-cylindrical stems extending therewithin, one of said followers having a diagonal web with a friction face and a horizontal web forming a spring seat, the other of said stems having a friction surface, a wedge shoe engaging said face and said surface, and resilient means compressed between said shoe and said horizontal web.

9. In a snubber, a main spring, top and bottom followers seated against opposite ends of said spring with semi-cylindrical stems extending therewithin for frictional engagement therewith, one of said stems having a diagonal web with a friction face and the other of said stems having a V-shaped friction surface, a wedge shoe engaging said face and said surface, and resilient means compressed between said shoe and one of said followers.

10. A friction device having a compression spring, top and bottom followers seated against respective ends thereof with stems extending therewithin in overlapping relationship, said stems presenting diagonally arranged friction surfaces, a wedge shoe in slidable engagement with said surfaces, and resilient means associated with and compressed between one of said followers and said shoe, one of said surfaces being of V shape and positioned at one side of the vertical axis of the device and the other of said surfaces extending through the axis.

11. A friction device comprising a compression spring, spaced followers seated against opposite ends of said spring with friction stems extending in overlapping relationship therewithin, diagonally arranged friction faces on said stems, a wedge shoe engaging said faces, and resilient means compressed between and abutting said shoe and one of said stems, the faces on respective stems being arranged at different angles with one of said faces extending through the axis of said device.

12. In a friction device, top and bottom followers, a compression spring therebetween presenting aligned friction surfaces therewithin, each of said followers having a stem portion within said spring in frictional engagement with said surfaces, a friction shoe engaging respective portions, and resilient means compressed between said shoe and one of said followers.

13. In a snubber, a compression spring, top and bottom followers having semi-cylindrical stems extending within said spring for frictional engagement therewith, one of said stems having a diagonal web with a friction surface and the other of said stems presenting a V-shaped friction face, a wedge shoe engaging said surface and face, and resilient means abutting said shoe.

14. A friction device having a compression spring, top and bottom followers seated against respective ends thereof with stems extending therewithin in overlapping relationship, said stems presenting diagonally arranged friction surfaces, a wedge shoe in slidable engagement with said surfaces, and resilient means under compression between one of said followers and said shoe, one of said surfaces lying at one side of the vertical axis of said device and the other of said surfaces extending therethrough.

15. In a friction device, a compression spring, top and bottom followers seated at opposite ends thereof and presenting therewithin substantially

semi-cylindrical friction stems for reciprocal movement, diagonally arranged friction surfaces on both of said stems, one of said surfaces being flat and the other V-shaped, a single friction shoe in slid able frictional engagement with both of said surfaces, and resilient means for urging said shoe into such engagement.

16. In a friction device, a compression spring, top and bottom followers seated at opposite ends thereof and presenting therewithin substantially semi-cylindrical friction stems for reciprocal movement, diagonally arranged friction surfaces on both of said stems, one of said surfaces being flat the other V-shaped, a single friction shoe in slid able frictional engagement with both of said surfaces, resilient means for urging said shoe into such engagement, and means on said shoe and one of said stems limiting the expansion of said device.

17. In a snubber, a coil spring, spaced followers seated against opposite ends thereof with semi-cylindrical portions in overlapping relationship with each other within said spring, each of said portions presenting a diagonal friction surface, a friction shoe engaging said surfaces, and resilient means compressed between and abutting said shoe and one of said followers.

18. In a friction device, a compression spring, top and bottom followers seated against opposite ends of said spring and having semi-cylindrical friction stems extending therewithin, one of said stems presenting a diagonal friction surface at one side of the vertical axis of said device and the other of said stems presenting a diagonal friction surface extending through said axis, a shoe in slid able frictional engagement with both of said surfaces, and resilient means for urging said shoe into such engagement.

19. An unsymmetric friction device comprising a compression spring, top and bottom followers having semicylindrical friction stems projecting in overlapping relationship within said spring,

converging diagonal surfaces on respective stems, a friction shoe in slid able engagement with said surfaces, and resilient means for urging said shoe into such engagement.

5 20. An unsymmetric friction device comprising a compression spring, top and bottom followers having semi-cylindrical friction stems projecting within said spring, converging diagonal surfaces on respective stems, a friction shoe in slid able frictional engagement with both of said surfaces, one of said surfaces being V-shaped and positioned at one side of the vertical axis of said device and the other of said surfaces extending through said axis, and resilient means for urging 10 said shoe into such engagement.

15 21. An unsymmetric friction device comprising a compression spring, top and bottom followers having semi-cylindrical overlapping friction stems extending therewithin for reciprocal movement, one of said stems having a spring seat at its extremity disposed interiorly of said spring, said stems presenting converging friction surfaces, a friction shoe having slid able engagement with said surfaces, and resilient means associated 20 with and compressed between said seat and said shoe for urging said shoe into engagement with said surfaces.

25 22. An unsymmetric friction device comprising a compression spring, top and bottom followers having semi-cylindrical friction stems extending therewithin for reciprocal movement, one of said stems having a spring seat at its extremity disposed interiorly of said spring, said stems presenting converging friction surfaces, a friction 30 shoe having slid able engagement with said surfaces, and resilient means compressed between said seat and said shoe, one of said surfaces being V-shaped and positioned at one side of the vertical axis of said device and the other of said surfaces extending through said axis.

35 DAVID M. LIGHT.
